LAUNDRY SYSTEM

Irvin A. Wilson, 1430 Tolma Ave., Pittsburgh 16, Pa.

Filed Dec. 10, 1957, Ser. No. 701,841

5 Claims. (Cl. 68—27)

This invention relates to laundry apparatus and particularly, to a washing and rinsing procedure, system or arrangement for articles of material, such as clothing, rugs, draperies, etc.

Although automatic washers are coming into increasing use, there is still a need for a more simple and inexpensive washing system that is of a semi-manual type. Also, the rinsing cycle of automatic washers is somewhat wasteful of rinsing water, and, as to some types of heavy articles, may not be sufficient and thus, require repeating the cycle. To meet both needs, I make use of a pair of adjacently positioned containers or wash tubs, such as commonly found in the laundry room of a home and, in such a manner, that water in the tubs may be used over and over again without draining the tubs, and irrespective of whether or not one tub is to be used as a washing tub or a first rinse tub or alternately, as both.

Heavier objects such as rugs, large draperies, etc., are more conveniently and effectively rinsed in a tub system and, in many cases, the tubs are used for rinsing other articles including clothing. A wringer may be positioned on the end partition wall between the tubs to wring out the articles after they have been washed or rinsed in one tub and before they are introduced into the other tub.

It is customary to drain water off from the wringer into the wash or first rinse tub to avoid contaminating the final rinse water. Tubbs of this type have bottom outlets or sewer connections adjacent their front or back end portions and are provided with plugs, so that a desired amount of water may be maintained in each of them. In an ordinary system, as thus outlined, it has been customary to handle the liquid or water separately in each tub, by means of separate supply faucets and separate drains. The tubs will be frequently drained and refilled to avoid adversely affecting the washing and rinsing operations; an article such as a small rug ordinarily requires a complete change of both wash and rinse water.

In accordance with my invention, I provide a system or arrangement wherein washing or rinsing water or liquid may be supplied to one tub and from that tub to the other in a continuous manner so as to utilize a common source of supply, to fully sweep scum and dirt from the surface and corners of the one tub forwardly into the other tub, and to produce a novel type of dirt and scum sweeping movement of the liquid within the tubs and from the other tub into the drain. This is done in such a manner that the main body of the liquid in each tub or container is, in effect, cleaned and kept directionally swept as the washing and rinsing operations progress and are completed. In fact, by way of example, employing my system or arrangement, I have been able to wash a dirty rug and then follow it immediately with an article of clothing, such as a white shirt. This appears to be impossible since no intermediate draining-off and replacement of the main bodies of liquid was accomplished. However, certain principles have been discovered and employed which make such an arrangement fully practical.

2

It has thus been an object of my invention to devise a new or improved system or arrangement for laundering articles and particularly fabrics in such a manner as to provide a more efficient employment of the cleaning water or liquid;

Another object has been to devise an arrangement which may utilize conventional laundry tubs, but in such a manner as to supply and circulate the water or cleaning liquid in a continuous, unidirectional sweeping manner, essentially in such a way as to automatically substantially fully renew the content of the tubs without the need for frequent draining and filling operations;

A further object of my invention has been to provide means for adapting laundry tubs or containers to a system or an arrangement of my invention;

A still further object of my invention has been to devise a circular movement of liquid within a pair of containers having a flow passage in a common partition wall therebetween, such that an agitated top layer of dirty liquid, lint, and scum will be continuously moved out of both tubs, while employing one as a washing or first rinsing chamber and the other as a final rinsing chamber, and while continuously supplying the liquid only to one of the containers from the other;

These and other objects of my invention will appear to those skilled in the art from the description and the illustrated embodiments.

In the drawings,

Figure 1 is a longitudinal section in elevation through a tub or container assembly or arrangement constructed and utilized in accordance with my invention;

Figure 2 is a top plan view of the container arrangement of Figure 1;

Figure 3 is an end section in elevation on the same scale as Figures 1 and 2, and taken along the line III—III of Figure 2;

Figure 4 is a fragmental front view in elevation through an intermediate partition portion of the assembly or arrangement of Figures 1 and 2, and on the same scale as such figures; this figure illustrates a modified or adaptor type of arrangement for one of the containers to provide it with a spillway;

Figure 4A is an enlarged fragmental perspective in elevation of the adaptor shown in Figure 4; this view shows the adaptor after it has been turned about 45 degrees clockwise of its position in Figure 4;

Figure 5 is a back view in elevation showing details of back connections employed with a construction such as shown in Figures 2 and 3;

And, Figure 6 is a greatly enlarged perspective back view in elevation of a slide or adjustable plate shut-off or control means employed in the construction of Figures 1 to 3, inclusive, and 5.

Referring particularly to Figures 1 to 3, I have disclosed an assembly of adjacent laundry tubs or containers 10 and 10' having a common upright end partition and connecting wall 11. These tubs or containers may be made of any suitable or conventional material, such as slate, aluminum, cast iron, porcelain or ceramic material. In these figures, I have illustrated an apparatus system or structural arrangement which may be employed to fully utilize the principles of my invention. In this connection, I have shown means 17 for supplying washing liquid to one container 10 which defines a final rinse chamber and whose liquid level *a* is provided by closing-off its drain opening or outlet 15*a* by a plug 16.

The other tub 10' defines a washing or first rinse chamber and a level *b* of water or liquid therein is maintained by closing-off its drain opening or outlet 15'*a* by a suitable plug 16'. A passage portion or spillway means 11*a* or 12*a* is provided for each of the containers or tubs 10 and 10'. The portions 11*a* and 12*a* have a vertically

spaced relationship with each other to define a lower level of liquid or water within the first chamber than in the second chamber. In addition, such spillways and particularly, the spillway 11a between the containers are so spaced and located that an effective agitating-sweeping or skimming-off action as to dirt, lint and scum is continuously maintained during the running of the liquid or water into the container 10. In other words, the movement is such as to cause the dirty liquid to rise into and remain in a top layer that is effectively removed as it is formed. On the other hand, a suitable operating level of clean water is maintained. A circulatory (circular) path of movement of the liquid is made possible and assured in the same direction in both of the containers 10 and 10'.

In accordance with my invention, the out-flow of liquid from the two containers or tubs is of a spillway or sweep-off type for a cutting or skimming action of out-flow of suspended scum, lint and dirt particles from positions that are substantially tangential to the circulation of liquid within the chambers of the containers. The position of inflow of liquid into the tub 10 is shown as substantially diagonal to the position of out-flow therefrom; this is also, for best results, true as to the tub 10'.

The tubs or containers 10 or 10' have been provided with similar reference numerals as to their common or similar parts, but have been distinguished by prime affixes, as applied to the second tub. The end walls of the tub unit construction or assembly are represented by 13 and 13'. Downwardly-backwardly-declining front walls 14 and 14' are shown in an opposed relationship with vertical back walls 12 and 12', and with bottom walls 15 and 15', define the second and first chambers of the respective containers.

The tubs 10 and 10', as shown particularly in Figure 2, have conventional drain openings or outlet portions 15a and 15'a through their bottom walls 15 and 15' adjacent a back end portion of the common partition wall 11. For normal operation of the system, the drain openings are closed-off by conventional plugs 16 and 16' of suitable resilient material, such as rubber. The drain openings 15a and 15'a are connected by threaded bushings 26 to a drain elbow part or fitting 25 at its upper, female branch portions 25a and 25b. The elbow or fitting 25 has a threaded pin or nipple sewer connection or portion 25c, as well as a backwardly-projecting externally-threaded pin or nipple portion 25d.

When a system of my invention is to be employed without the desired type of spillway drain passage 12'a, to quickly adapt a conventional tub arrangement, I provide a spillway tube 30 (see Figures 4 and 4A) whose lower end portion 30a is tapered to fit within and make a seal with the taper of the drain or outlet portion 15'a. In such an adaptation, supply faucets (not shown) of the container 10' need not be used. The upper end of the tube 30 is provided with a sleeve-fitting or threaded-on end closure 30b which has a rectangular side opening or passageway portion 30c. As shown in Figure 4, liquid b is also maintained by such means at a tangential location as to the path of movement of the liquid.

As shown particularly in Figure 2, the source of liquid, such as a common hot and cold water mixer type of faucet arrangement 17 is shown provided with an out-swung spout or nozzle 17a to further a rotating, clockwise movement, such as shown in this figure, when the nozzle is swung to the position of Figure 2. The circulating or rotating movement of the liquid or water in the second chamber (defined by container 10) is indicated by arrows l of Figure 2, by arrows m as to the first chamber (defined by container 10'), and by arrows n to indicate the out-flow from the spillway passage portion 12'a of the rinse chamber.

When the container or tub 10' is employed in accordance with my system, using a back corner spillway-

outlet passage 12'a, I have provided means for closing-off such passage when the tub 10' is to be used for other purposes, and when open, for receiving liquid flow tangentially-outwardly of the circular path of movement of the liquid in the tub 10' to discharge it into a drainage or sewage system. In Figure 6, I have shown an adjustable, apertured slide plate member 27 of disc-like or circular shape that has a central, rectangular-shaped passageway or bore 27d that corresponds in size and shape to the size and shape of the passage 12'a in the container wall, see Figures 1 and 3. The plate 27 also has an elongated bottom slot 27a and a pair of similar, elongated slide slots 27b and 27c. A backwardly-projecting pin 27e is employed as an operating handle for adjusting the positioning of the plate member 27 with respect to the passageway 12'a.

As shown particularly in Figures 1, 2, 3 and 5, the plate member 27 is adjustably carried on the inner side face of a drain fitting or connector 18. Bolt and nut assemblies 19 are carried by mounting holes in the back wall 12', extend through elongated slots 27b and 27c, and are carried by mounting holes 18b and 18c in the connector 18. A threaded set bolt or screw 28 (see Figure 3) is carried by the connector 18 and projects into alignment with the bottom slot 27a of the adjustment plate member 27. When through bolt and nut assemblies 19 are loosened, the plate 27 may be adjusted along its slots 27b and 27c, as guided by the set screw 28 along its slot 27a. Thus, the plate 27 may be positioned to shut-off or open the outlet passage portion 12'a.

Thus, it is apparent that a fluid-sealed-off tight joint may be effected by tightening down on the bolts 19 after the adjustment has been accomplished.

Soiled liquid passes through a bore within the drain connector 18 and is carried by its male threaded nipple or pin end portion 18e to a down-pipe 20 and an annular connector elbow part 22. Internally-threaded female collars 21 secure the pipe 20 on the nipples of the parts 18 and 22. As shown in Figures 3 and 5, the elbow 22 may have its other side nipple or pin end portion 22b closed-off by plug 23 (see also Figure 2), although it may be provided with parts 18, 20, etc., if the tub 10 is to constitute the first tub rather than the tub 10'. In this case, the side end portion 22a would be provided with a plug corresponding to 23. As shown particularly in Figures 3 and 5, a front threaded pin or male end portion 22c is connected by a pipe section 24 and its collar to a back pin or threaded nipple end portion 25d of drain connector 25.

As shown in Figures 2 and 3, c has been employed to indicate the distance between the center line of the passage portion 11a and the inner upper edge of the front walls 14 and 14'. The dimension d is taken between the vertical center line of the passage portion 11a and the inner edge of the back walls 12 and 12'. As shown particularly in Figures 1, 3 and 4, e represents the vertical distance from the top edge of the tubs to a horizontal center line of the passageway 11a, and e' represents the vertical distance from such center line to the inside of the bottom walls 15 and 15' of the containers.

As shown in Figures 1 and 2, f indicates an end or cross dimension between the inner side of end wall 13' and a vertical center line through the passageway 12'a. The end or cross dimension g extends from such vertical central line to the side of the partition wall 11 that faces the rinsing chamber. In Figures 1 and 3, i represents the distance between the top edge of the container 10' to a horizontal center line through the drain passage portion 12'a. On the other hand, h represents the distance between such center line and the inside of the bottom wall 15'.

It must be emphasized that the position of the spillway passage 11a is critical from the standpoint that it must be located forwardly beyond a center line through the container from the position at which the liquid is supplied.

In other words, as shown in Figure 2, the passage 11a must be located forwardly of the liquid supply means 17 and beyond an endwise-extending center line through the partition 11 and at a corner location such that it lies substantially tangential to the circulatory path of the movement *l* of the liquid or water within the tub 10. In a like manner, the drain spillway should be located near a remote back corner of the rinse tub 10', off-center with respect to such tub, and in a substantially tangential position with respect to the circulatory path of movement *m* of the liquid therein. In this connection, an enclosed or encircled rectangular passage portion (such as 12'a) provides much better results than a rounded-corner passageway.

Although, an improved type of skimming-off action is attained by reason of the type of circulating movement in the chambers, and a substantially full and complete type of action is essential for the final rinsing chamber of container 10 and is assured by the shape, location and nature of the intermediate spillway 11a, a slightly lesser efficiency of layout may be permissible in the washing or initial rinsing chamber of the container 10'. Thus, the spillway tube 30 may be used for adaptation purposes. It will be noted that both the passageways 12'a and 30c are located behind an intermediate or longitudinal center line through the tubs and adjacent back corners of the tub 10'. The effective flow size of the rectangular side opening in the outlet portion 30b of the tube 30 should be at least the same as that of the intermediate passage or spillway 11a.

Contrary to what might appear, if the circulation or path of movement of the liquid within the container 10 is clockwise, then the circulation or path of movement *m* within the rinse container 10' will also be clockwise and not counterclockwise. The drain plugs 16 and 16' need only be withdrawn at the completion of the washing or laundering operation, in that employing my system, the liquid or water in both of the containers 10 and 10' is kept so fresh and clean that a series of articles, whether white or colored, very dirty or slightly dirty, may be processed in series-progression, without adversely affecting the rinsing or washing operations, and without spoiling or dulling the white goods, for example.

The rectangular shape of the spillway passage portion 11a which is important, provides a greatly improved skimming- or screening-off action of scum and dirty liquid level from the top level of the washing bath and is effective in providing a desired clean water level in the bath. The passage portion 11a has a greater horizontal than vertical dimension or extent to impart a like shape to the stream or flow of water therethrough. As shown, both baths are filled and kept circulating by a continuous supply of water or liquid from the spout 17a. This provides a relatively high level of liquid in both baths, but a slightly lower level *b* in the washing or first rinsing chamber than the level *a* in the second or final rinsing chamber (see Figure 4).

The lower level of liquid *b* in the container 10' is maintained by providing the spillway outlet passage portion 12'a (or an outlet portion 30c of the tube 30), the level of whose open-mouth corresponds substantially to the desired top level of the bath. It is important that the size or extent of the opening provided by the outlet passageway of the rinsing container 10' be as large as or of substantially the same size or flow area as the spillway passage portion or outlet 11a from the container 10. Also, if as is desirable, a side outlet passageway portion 12'a is provided for the chamber 10', it will have substantially the same rectangular shape and dimensions as that of the passage portion 11a.

The maintenance of a different level of operation in the two containers also assures that the continuous flow of water or liquid is always in one direction between the washing and rinsing tubs and never a counterflow, and such that scum and dirty water will spill out of each chamber never to return thereto to leave the remaining

water in the containers relatively clean and effectively usable for washing and rinsing operations. The employment of a spillway passage of greater horizontal than vertical dimension and its above-explained location, are important in this connection.

In accordance with my invention, the water or liquid is supplied throughout the cleaning or laundering operations, until they have been completed. If a hand type of washing operation is to be accomplished in the chamber of 10', the flow of water from the spout 17a may be turned-off until it is completed. At such time, the flow may be again started and continued until the tubs have been cleared of soap, lint, etc. When the tubs are to be used as for initial and final rinsing of clothes washed by a washer, the supply of liquid or water may be effected continuously during the operation.

Although the inner contour of the containers or tubs 10 and 10' is substantially rectangular, the "live," continuous, unidirectional, activated flow of water within the containers is such that it sweeps along the corners and tangentially from one container into the other and out of the other into a sewer or drain connection. Since the out-flow and the supply of water is maintained substantially constant, the level of water within the chambers is also maintained substantially constant.

It is important to note that although others skilled in the art have employed tub arrangements wherein there has been an outflow from one into another and an upper-level outflow from the other, my arrangement is based upon a new principle of flow, such that the water remaining in the tubs is substantially fully clean for rinsing and cleansing operations. In this connection, the tangential location and the nature of my spillways are important factors and in connection with a circulatory type of agitated flow. That is, a top-edge overflow between chambers makes my type of circulating movement impossible and a vertically-extending or open type of circular or rounded corner off-flow spillway opening or enclosed passageway has been found ineffective as to a full skimming-off action. Also, the circulatory type of flow has been found to be highly important in forming into and moving the dirt, scum, lint and soap particles as an upper suspension layer of the baths and in maintaining them as a top layer of a nature and type that an effective skimming-off action can be attained and the main body of liquid within the baths will be maintained clean for continuous or uninterrupted operation.

It may also be noted that I contemplate providing means 18 on each of the containers 10 and 10', if the particular container (right or left) that is to provide the first rinse or wash chamber or bath is not known at the time of the sale for the installation involved. However, once the layout and location of the washing apparatus has been selected and the installation has been made, only one means 18 is needed and, for this reason, I have shown only one in the drawings as representative of the utilization.

The levels of liquid or water *a* and *b*, shown in the drawings, represent stationary levels or levels at the time that the baths are quiescent and no liquid is being introduced. However, when flow of liquid is being effected by the introduction of the liquid through the spout 17a, the level in the chamber of the first tub 10 rises above the level *a* to substantially a raised level represented by the top wall of the passageway 11a. In other words, the supply of liquid or water is made sufficient to first provide a kinetic outflow of the liquid through passageway 11a into the chamber of the second tub 10' and, secondly, in order that the vertical extent or width of the passageway 11a will project below the activated top surface of the water in the chamber 10 and beneath the activated layer of dirt and scum carried along its top. In a like manner, the level of liquid within the chamber of the second tub 10' is raised to provide a similar type of action and outflow as to the passage 12a.

What I claim is:

1. A laundry apparatus employing a pair of adjacently-positioned liquid containers having at least one separation wall therebetween and wherein one container has walls defining a final rinse chamber and the other container has walls defining an initial rinse or wash chamber which comprises, means adjacent an upright wall of the one container to fill the chambers with liquid, said means having a portion positioned to impart a circular path of movement of liquid within the final rinse chamber, a flat-surfaced spillway passage portion through said separation wall adjacent an upper portion of the one container to define the level of liquid in the final rinse chamber, said spillway passage portion having a positioning that is forwardly beyond an intermediate location between the first-mentioned upright wall of the one container and an opposite wall of the same container; said spillway passage portion having a substantially tangential positioning with respect to the circular path of movement of the liquid within the final rinse chamber to drain surface scum from the final rinse chamber into the initial rinse chamber and to, with the above-defined positioning, set-up a second circular path of movement of liquid within the initial rinse chamber corresponding to the direction of the circular path in the final rinse chamber; a second flat-surfaced spillway passage portion having a positioning adjacent a back corner of the other chamber and backwardly beyond an intermediate location between opposed upright walls of the other container and having a lower height than said first-mentioned spillway passage portion, said second spillway passage portion being open from the initial rinse chamber adjacent an upper portion thereof to define the level of liquid within the initial rinse chamber and discharge surface scum at a lower level from the initial rinse chamber than from the final rinse chamber, and said second-mentioned spillway passage portion being open solely in a substantially tangential positioning with respect to the second circular path of movement of liquid within the initial rinse chamber to provide a directed discharge flow from the initial rinse chamber in alignment with the circular path of flow created therein to complement the existing circular flow.

2. A laundry apparatus as defined in claim 1 wherein the opening of said second-mentioned spillway passage portion projects through a back wall of the other container, an adjustable slide-plate shut-off means is carried by the other container in a cooperating position with said second-mentioned spillway passage portion, and a connector cooperates with said adjustable means to discharge liquid from said second-mentioned spillway passage to a sewer.

3. A laundry apparatus as defined in claim 1 wherein the other container has an upwardly-projecting outlet tube provided with a closed upper end having a single open side portion directed toward the circular path of flow and defining said second-mentioned spillway passage portion.

4. A laundry apparatus having a pair of upright rec-

tangular containers in an end-to-end connected relationship and wherein, the containers have a common partition wall therebetween and having bottom, front, back, and end walls, and the walls of the one container define a final rinsing chamber and the walls of the other container define a first rinsing chamber which comprises, water injection means cooperatively positioned with respect to the back wall of the one container for filling its chamber and imparting a circular path of movement of water therein in one direction and for continuously supplying water thereto during a laundering operation, spillway means for discharging surface water and scum from said final rinsing chamber and for initiating a second unidirectional circular path of fluid movement in said first rinsing chamber which flows in the same direction as the path of movement in the chamber of the one container, said spillway passage means comprising a rectangular spillway passage portion through the partition wall at an upper-front corner portion thereof which defines the level of liquid within the final rinsing chamber, said spillway passage being positioned substantially tangential to the circular path of movement within said final rinsing chamber, a second rectangular spillway passage portion open through a wall of the other container adjacent a back corner thereof to discharge dirty water and surface scum from the first rinsing chamber, the opening of said second-mentioned spillway passage portion being positioned toward and tangentially of the circular path of movement of water within the first rinsing chamber, and said second-mentioned spillway having an inlet opening that is located substantially above the bottom wall of the other container and slightly below the first-mentioned spillway passage portion to maintain a level of water within the first rinsing chamber slightly below the level within the final rinsing chamber.

5. A laundry apparatus as defined in claim 4 wherein a sliding-plate device is mounted on the back wall of the other container to open and close said second-mentioned spillway passage portion, said sliding plate device has an apertured disc adjustably secured on the back wall of the other container, said disc has a spillway passageway slot therein of rectangular shape that defines said second-mentioned spillway passage portion and is open to the first rinsing chamber, a connector is mounted on the back wall of the other container in a cooperating relationship with said disc and has a passageway to receive water from the passageway slot in said disc, and sewer-connecting pipe means extends from said connector.
